(57) **CLAIM**

The ornamental design for a canister lid, as shown and described.

DESCRIPTION

FIG. 1 is a front plan view of a canister lid with the lid in an open position, showing our new design;

FIG. 2 is a front plan view thereof with the lid closed;

FIG. 3 is a back plan view thereof with the lid in an open position;

FIG. 4 is a back plan view thereof with the lid closed;

FIG. 5 is a right side plan view thereof with the lid in an open position;

FIG. 6 is a right side plan view thereof with the lid closed;

FIG. 7 is a left side plan view thereof with the lid in an open position;

FIG. 8 is a left side plan view thereof with the lid closed;

FIG. 9 is a top plan view thereof with the lid in an open position;

FIG. 10 is a top plan view thereof with the lid closed;

FIG. 11 is a bottom plan view thereof with the lid in an open position;

FIG. 12 is a bottom plan view thereof with the lid closed;

FIG. 13 is an isometric view thereof with the lid in an open position; and,

FIG. 14 is an isometric view thereof with the lid closed.

The broken lines are for purposes of illustrating unclaimed portions of the canister lid and form no part of the claimed design.
